UNITED STATES PATENT OFFICE.

HERBERT COTTRELL, OF NEWARK, NEW JERSEY, ASSIGNOR TO L. A. SAYRE & CO., OF NEWARK, NEW JERSEY, A FIRM.

TICKET-PUNCH.

SPECIFICATION forming part of Letters Patent No. 708,465, dated September 2, 1902.

Application filed January 2, 1902. Serial No. 88,110. (No model.)

To all whom it may concern:

Be it known that I, HERBERT COTTRELL, a citizen of the United States of America, residing in the city of Newark, county of Essex, 5 and State of New Jersey, have invented certain new and useful Improvements in Ticket-Punches, of which the following is a specification.

My invention consists in producing a novel 10 reservoir for ticket-punches, its most important features being that the reservoir-space adapted to retain the cuttings is entirely recessed within the body of the die-holding member of the ticket-punch below the die, 15 and its discharge-orifice provided with a cover, which instead of folding open or shut upon pivot or hinge is adapted to slide back in guides longitudinally to an open position and be prevented from being removed from the 20 guides by a stop-pin upon the cover, which projects within the recessed receptacle, thus guarding against the separation or loss of the cover, and which may be locked in a closed position by means of a latch. This construction produces a secure reservoir, enhances 25 the appearance of the implement, cheapens the manufacture thereof, simplifies the operations to produce it, removes the possibility of loss of parts, and the cover when open is slid 30 back out of the way, and thus prevents liability to catch, bend, or break.

Referring to the accompanying drawings, which form part of this specification, Figure 1 is a vertical view of the ticket-punch embodying my invention. Fig. 2 is an obverse

exterior view showing cover in closed position. Fig. 3 is a vertical section showing interior of receptacle and comprising parts with cover closed. Fig. 4 is a transverse sectional view to show dovetail cover, stop-screw, exterior push-knob, and slot. Fig. 5 is a vertical section showing interior of receptacle and comprising parts with cover open.

Figs. 1 to 5, inclusive, show the various parts of my device and the operation thereof. 45

A is the die-holding member.

b is the punch-holding member.

c is an expansible spring to open the jaws of the punch; d, receptacle-cover.

e is the stop-screw to limit the movement 50 of the receptacle-cover; f, spiral latch-spring; g, push-knob; h, latch for fastening cover, and a' a slot through which latch moves.

Without limiting myself to the precise details shown, what I claim, and desire to secure 55 by Letters Patent of the United States, is—

In a ticket-punch the combination of a receptacle for the clippings recessed in the die-holding member, a cover upon the lower side thereof adapted to slide longitudinally in 60 guides; a stop-screw inserted in the said cover to serve as a push-knob to open and close the same; and a latch to fasten the said cover in a closed position, substantially as described.

This specification signed and witnessed this 65 30th day of December, 1901.

HERBERT COTTRELL.
